UNITED STATES PATENT OFFICE

170,504

COMBINED MEMO PAD AND PENCIL HOLDER

Edward B. Lee, Chicago, Ill., assignor of one-half to Morton Marks, Chicago, Ill.

Application May 1, 1953, Serial No. 24,792

Term of patent 14 years

(Cl. D74—1)

To all whom it may concern:

Be it known that I, Edward B. Lee, a citizen of the United States, residing at Chicago, in the county of Cook and State of Illinois, have invented a new, original, and ornamental Design for a Combined Memo Pad and Pencil Holder, of which the following is a specification, reference being had to the accompanying drawing forming a part hereof.

Figure 1 is a side perspective view of a combined memo pad and pencil holder, showing my new design; and

Fig. 2 is a side elevational view thereof.

The side of the combined memo pad and pencil holder opposite to that disclosed in Fig. 2 is substantially the same as that shown in said figure.

I claim:

The ornamental design for a combined memo pad and pencil holder, substantially as shown and described.

EDWARD B. LEE.
